UNITED STATES PATENT OFFICE.

BURTON L. LAWTON, OF MERIDEN, CONNECTICUT, ASSIGNOR, BY MESNE ASSIGNMENTS, TO THE UNIT COIL COMPANY, OF JERSEY CITY, NEW JERSEY, A CORPORATION OF NEW JERSEY.

MULTIPLE-CYLINDER-MOTOR IGNITION APPARATUS.

No. 911,414.

Specification of Letters Patent.

Patented Feb. 2, 1909.

Application filed June 19, 1907. Serial No. 379,732.

To all whom it may concern:

Be it known that I, BURTON L. LAWTON, a citizen of the United States, residing at Meriden, New Haven county, Connecticut, 5 have invented certain new and useful Improvements in Multiple-Cylinder-Motor Ignition Apparatus, of which the following is a full, clear, and exact description.

My invention relates to ignition apparatus 10 for internal combustion motors and particularly of the four cycle multiple cylinder type. With such motors and especially on cars having four or more cylinders, difficulty is often encountered,—for instance, under unusually 15 heavy loads such as steep upgrades,—by what is termed cross firing. This causes “bucking”, which is not only very annoying but sometimes dangerous. It is my object to prevent this.

In multiple cylinder ignition systems it is customary to employ a jump spark igniter or plug in each cylinder fired by separate induction or Ruhmkorff coils, one for each igniter. Four cycle motors have one ignition and 25 working stroke of each piston once in two complete revolutions of the main shaft. A four cylinder engine, therefore, has one ignition at each half revolution of the main shaft. There is, therefore, at the moment of 30 ignition in one cylinder, some other cylinder with a full charge of air and fuel, but uncom-pressed. This charge is inflammable and sometimes is accidentally ignited, especially when the mixture is rich. This accidental 35 ignition I believe to be due to the action of static and magnetic induction. I have found it possible to prevent it by the use of a soft iron plate or plates between the induction coils. These coils in boxes are prefer- 40 ably interchangeably mounted in a casing, so I prefer to provide a plate on each side of each coil within its box. There are then two layers of metal between adjacent coils which serve to prevent any cross induction between 45 the separate coils.

The drawing is a diagram showing a four cylinder motor of the four cycle internal combustion type with jump spark igniters and induction coils. The four coils are shown in 50 their boxes and all inclosed in a case, the case and one box being shown in section. The cylinders 1, 2, 3 and 4 are provided with the usual valves and pistons connected to cranks 10, 20, 30 and 40.

55 The igniters 11, 21, 31 and 41 have one

terminal of each grounded on the engine frame and the other terminals connected to the terminals 12, 22, 32 and 42 in the bottom of the casing 5. The casing preferably has a center partition 50 which strengthens it and 60 divides it into two compartments.

The battery or source of current 6 is grounded at 60 on the engine frame and connected to terminals 61 in the casing. It is often desirable and, in fact, customary, to 65 provide an additional battery such as 62 and a switch with the contacts 63 and 64 and switch arm 65, so that either battery may be thrown into or out of circuit readily.

A circuit closer or switch is provided, 70 which is driven at a rate proportioned to the speed of the motor, as is customary, and which has a revoluble member 7, grounded at 70 on the engine frame. The contacts 71, 72, 73 and 74 are connected to the terminals 75 51, 52, 53 and 54 in the casing.

Each of the coil boxes 81, 82, 83 and 84 is independently removable from the casing and contains a primary winding P, a sec- 80 ondary winding S and a condenser C, the latter being bridged or shunted across the vibrator terminals B and V. The primaries have terminals P', P², P³, and P⁴ on the exterior of the boxes which engage the contact strip 66 in the casing, which is connected to 85 battery terminal 61. The secondaries have terminals S', S², S³ and S⁴ on the bottom of the boxes engaging the terminals 12, 22, 32 and 42 which are connected to the igniters. The other terminals of the coil windings in 90 each box are connected to the bridge B. The armatures, such as V, are connected to terminals C', C², C³ and C⁴ on the exterior of the boxes which engage the contacts 55, 56, 57 and 58 in the casing which are connected 95 to the terminals 51, 52, 53 and 54.

In the position shown in the drawing, the primary circuit may be traced from battery 6 to terminal 61, contact strip 66, contact P', primary winding P, bridge B, vibrator V, 100 contacts C' and 55, terminal 51, contact 71, circuit closer 7, ground 70 to 60 switch 65, contact 63 to the battery. The secondary circuit may be traced from the secondary winding S, terminals S' and 12, igniter 11, 105 through engine frame to ground 70, circuit closer 7, contact 71, terminal 51, contacts 55 and C', armature V and bridge B back to the secondary. The charge in cylinder 1 is thus ignited. It is customary to fire the cylinders 11.

in the order of 1, 2, 4 and 3 and the circuits as shown are so ordered, the circuit closer rotating to the right, so as to successively complete the circuits through the coil boxes 81, 5 82, 84 and 83. It is obvious that contacts 72 and 74 might be interchanged so that the order of firing would be 1, 4, 2 and 3, the valves being properly set.

Sometimes the charge in cylinder 2 which, 10 as shown and described, is supposed to follow cylinder 1 at 180° , is ignited at the same time as cylinder 1. I have been able to prevent this by eliminating or reducing the induction effect of the coils in box 81 on the 15 coils in box 82 by means of a soft iron plate placed between the coils. Preferably I place a plate or sheet such as 9 and 90 on each side of each coil within the box which is customarily of wood. There is then no danger 20 of the cross induction, no matter what the position or arrangement of the boxes in the casing. The same difficulty of back or cross firing is encountered in four cycle engines of more than four cylinders and may be avoided 25 by the use of my invention; so also in engines of the two cycle type and two or more cylinders, the cross-firing may be avoided by inductively insulating the coils for the different cylinders.

30 I wish it clearly understood that I consider my invention in its broad sense to cover the use of any suitable magnetic material in the manner set forth for preventing the inductive cross firing. Experiment with 35 a system may show that the cross firing occurs only in one cylinder, in which case it will be only necessary to protect the coil for that cylinder by a layer of iron or equivalent material. Of course the iron may entirely 40 surround the coil, but this is usually not necessary. The invention is applicable to any number of coils and with stationary units, as well as removable units.

What I claim is:

45 1. In an ignition system the combination of a multiple cylinder internal combustion motor of the four cycle type, with ignition devices, a source of primary current, induction coils having their primary windings 50 adapted to be connected to the source of current and having their secondary windings adapted to be connected to the ignition devices, means for bringing the ignition devices successively into operation and means for 55 preventing interference between the coils to prevent cross firing.

2. In a power system, a multiple cylinder motor of the internal combustion type, an ignition device for each cylinder, a source of 60 current, a plurality of induction coils arranged adjacent to each other and having their primary windings connected to the source of current and having their secondary windings connected to the ignition devices, 65 means for preventing cross induction be-

tween the coils and a circuit closer for bringing the ignition devices successively into operation in a predetermined order, whereby back firing is prevented.

3. In a power system, the combination of 70 a multiple cylinder motor, an ignition device for each cylinder, a source of current, a plurality of interchangeable induction units removably mounted in a casing, the primary windings being connected to the source of 75 current, and the secondary windings being connected to the ignition devices, magnetic insulating plates arranged on the opposite sides of the units outside of both the primary and secondary windings, and means for making and breaking the circuits in a predetermined order.

4. Multiple cylinder induction ignition apparatus comprising the combination with 80 a multiple cylinder engine having ignition devices of a casing, a plurality of coil units removably mounted in the casing, one for each cylinder, each unit consisting of a box containing primary and secondary windings, and plates of magnetic insulating material 90 on the opposite sides of the primary and secondary windings and extending above and below the ends thereof.

5. Multiple cylinder motor ignition apparatus comprising a casing, a plurality of boxes 95 removably mounted therein, primary and secondary windings in each box, a vibrator in circuit with each primary winding, separate contact terminals carried by each box for the primary and secondary windings 100 therein, a source of current, a common terminal in the casing for the primary winding contacts, a third contact carried by each box and common to the primary and secondary windings therein, separate terminals 105 in the casing for said common contacts, ignition devices adapted to be thrown into the secondary circuits and to be brought into operation at certain times and means for preventing untimely sparking.

6. Multiple cylinder motor ignition apparatus comprising a casing a plurality of boxes removably mounted therein, primary and secondary windings in each box, a vibrator in circuit with each primary winding, 115 separate contact terminals carried by each box for the primary and secondary windings therein, a source of current, a common terminal in the casing for the primary winding contacts, a third contact carried by each 120 box and common to the primary and secondary windings therein, separate terminals in the casing for said common contacts, ignition devices adapted to be operated by the secondary induced currents and a magnetic insulating device arranged between the coils of two adjacent boxes, whereby untimely firing is prevented.

7. Multiple cylinder motor induction ignition apparatus including a multiple cylinder 130

engine having ignition devices in combination with a casing, a plurality of independently removable boxes mounted therein, primary and secondary windings contained in each box and a magnetic insulation device arranged between the coils of adjacent boxes, whereby untimely ignition is prevented.

8. Multiple cylinder motor induction ignition apparatus including a casing, a plurality of coil units mounted therein in proximity to one another and each consisting of primary and secondary windings and a vibrator, a source of current, an ignition device operated by the current in each secondary winding and means for preventing interference between the primary of one coil and the secondary of another coil, whereby improper firing is avoided.

9. Multiple cylinder motor ignition apparatus including an ignition device for each cylinder, an induction coil for each ignition device, said coils being mounted in proximity to one another, each coil including primary and secondary windings and a vibrator, a source of primary current, means for bringing the ignition devices into operation successively and means for preventing interference between the coils whereby improper ignition is prevented.

10. In combination with an engine having a plurality of cylinders and a single crank shaft with pitman connections to the respective cylinders, a plurality of induction coils connected to successively ignite the

charges in the respective cylinders in a pre-determined order, and a magnetic shield located in operative relation to intercept the magnetic flux between two adjacent coils, the cylinders of which fire in an immediate sequence.

11. The combination with a plurality of open magnetic circuit coils arranged in close proximity one with another, of an electric circuit for each coil including its primary winding, a plurality of independent open circuits corresponding in number to and including respectively the secondary windings of the coils, means for successively closing and opening the several circuits of the primary series, and means for preventing the induction of currents in each secondary winding by the influence of its immediately adjacent secondary.

12. The combination with a plurality of open magnetic circuit coils grouped in proximity to one another, of an electric circuit for each coil including its primary winding, a plurality of independent open circuits corresponding in number to and including respectively the secondary windings of the coils, a commutator for successively closing and opening the several primary circuits, and an open magnetic circuit shield arranged intermediate each pair of adjoining coils.
